DAM AND METHOD OF MAKING SAME

Application filed February 25, 1931. Serial No. 518,280.

This invention relates to improvements in dams, and it consists of the constructions, combinations, arrangements and method herein described and claimed.

5 An object of the invention is to build a rock-fill dam along such lines that earthquakes and other causes of internal disturbance will not be able to flatten it and generally do no more harm than interrupt the otherwise flat face of the water tight membrane with a shallow concavity.

Another object of the invention is to provide for rock-fill dams a flexible waterproof diaphragm on the upstream side, this being 15 backed by a mobile stratum which has the special quality of so disseminating any local relaxation either in its own structure or in its rock base that but the slightest depression will occur in said diaphragm by virtue 20 of its flexibility, and that depression over so wide an area that it will hardly be perceptible and that none of the joints will be ruptured.

25 A further object of the invention is to introduce a thick bed or blanket of sized, washed and screened river gravel between the rock-fill of a dam of that type and the ultimate outer "skin" or concrete, waterproof diaphragm.

30 A further object of the invention is the building of auxiliary or secondary fills, parallel to the main fill, yet apart from the main fill, so that the work of placing the gravel facing or cushion, as well as the concrete diaphragm, can proceed at the same time that the main fill is being formed.

Other objects and advantages will appear in the following specification, reference being 40 had to the accompanying drawings in which

45 Figure 1 is a vertical section of a portion of a rock-fill dam embodying the principles of the invention.

Figure 2 is a sectional diagram illustrating 50 the method of making the dam whereby the ultimate water tight membrane occupies an angle considerably flatter than the angle of repose ordinarily assumed by dumped rock, gravel or the like.

55 Figure 3 is a detail sectional view illustrating some of the details of the flexible dia-

phragm, especially the mode of anchoring the water tight membrane to its foundation slab.

Figure 4 is a similar sectional view illustrating the details of the footing.

Figure 5 is a sectional perspective view of a portion of the flexible diaphragm, showing how the water tight membrane is superimposed on its foundation slab.

Figure 6 is a detail sectional view particularly showing one of the water stops.

Figure 7 is a sectional view of a canyon showing how the ends and bottom of the dam are embodied in the rock walls.

Figure 8 is a cross section taken on the line 8—8 of Figure 7, showing in detail how one end of the dam is embedded in the adjacent rock wall.

The outstanding feature of the invention resides in what is herein known as a flexible diaphragm generally denoted 1 (Figs. 1 and 3). This diaphragm involves mechanical details of construction which are fully described later, and it is for the purpose of making clear how the integrity of this diaphragm is intended to be preserved in practice, that the method of construction of the rock base and its constituents is described first.

It is a natural fact that rocks dumped on a pile will fall over each other until they come to rest at an angle of repose which is about 1.4 to 1, or in other words, 1.4 feet of base dimension for every foot of altitude. An internal disturbance in the rock pile of any serious proportions is likely to upset the balance of this natural angle of repose so that some of the rocks are either loosened and sent tumbling down the sides or are caused to fall into a hole in case the disturbance causes an internal sinking.

Where this is true of an ordinary rock pile it is equally true of a rock-fill dam only here the consequences are likely to be disastrous if an impounded volume of water depends upon the dam for its retention. Therefore, one of the first purposes is to so flatten out the face of the dam that it will not be possible for any ordinary earthquake to flatten it further. This is accomplished by producing

a 1.6 to 1 ratio, in other words approximately 1.6 foot base dimension for every foot altitude.

At this point it must be explained that this 5 ratio is not conclusive. The 1.6 to 1 ratio is merely cited for illustration, and is intended to show one example of base extension beyond that which would be found if the material were permitted to assume an angle of repose 10 of its own accord.

Reference is made to the drawings. A rock base shown at 2 (Figs. 1 and 2) comprises a main rock-fill 3 and a plurality of auxiliary fills 4, 5, 6, 7, etc. (Fig. 2). In 15 order to flatten the face of the rock base 2, in other words, to lessen the steepness of the natural angle of repose 8 (Fig. 2), the succeeding fills 4, 5, 6, 7, etc., are dumped upon each other but are so proportioned that their 20 widths along the lines 9 are progressively less toward the top of the dam.

As a result of this construction, the face 10 of the rock base (Fig. 2) will be flatter, so to speak, than the natural angle of repose 25 8. It is perfectly plain that if even a flatter face 10 were desired, the only requirement would be to dump more rock in the fill 4 in order to extend it out farther from the main 30 rock fill 3, and then dump the succeeding auxiliary fills 5 in proportionate volumes.

In this way the face 10 can be made as flat as desired, and rather than adhere to the 1.6 to 1 ratio the proportion arrived at might be 1.8 to 1, 2 to 1, etc. The auxiliary fills 4, 35 5, etc., are made in lifts that are most convenient, but in the case of the dam under consideration was regarded as 25 feet high.

It is to be noted that in dumping these auxiliary fills the face slopes are bound to 40 assume the natural angle of repose 1.4 to 1. The inclined faces of the succeeding fills are, therefore, parallel to the face 8 of the main rock-fill 3. The so-called flattening of the face 10 (Fig. 2) is not produced by disturbing 45 the material in the fills 4, 5, etc., in any way but by successively diminishing the volume of these from bottom to top of the dam, so that a mean face line 11 (Fig. 2) will stand at a lesser angle than the angle of 50 the face 8.

The immediately preceding description is intended to emphasize how it is possible to produce a face 10 (Fig. 2) flatter than the natural angle of repose of the face 8. It is not 55 a specific requirement that the rock fill 3 be completed in its entirety before the auxiliary fills 4, 5, etc., are begun. The plan would be to carry the main rock fill 3 to an appropriate altitude, say 35 feet, and then begin 60 the auxiliary fill 4. All that needs be known is the base dimension of the auxiliary fill 4 as well as those of the succeeding auxiliary fills, and when these are made progressively smaller the mean face line 11 will be found 65 unimpaired in the completed rock base 2.

This mode of construction interrupts the face 10 (Fig. 2) with a succession of set-backs 12. These appear small on the drawing, but in practice they are wide enough to support a spur track which will be extended across the 70 canyon 13 (Fig. 7) as the auxiliary fill progresses.

A gravel facing 14 (Figs. 1 and 2) is dumped upon the face 10. This gravel facing comprises a large body of sized, washed and screened river gravel between the main dumped rock-fill 3 and a concrete, watertight diaphragm referred to later. This gravel facing or bed is not fine material. It is composed of stones from 1 to 3 inches in diameter; absolutely free from dirt, sand or fine pieces. As previously stated, it is sized in order that it may quickly readjust itself in case of settlement, which it would not do if fines of any kind were used in the gravel 80 blanket. The gravel facing thus constitutes a mobile stratum which has the property of flowing into any settlement in the rock base 2 and so distribute the depression over an extremely wide area in order to avoid any sudden drop or break in the flexible diaphragm 1 which is laid directly on the gravel facing 14 as shown. The gravel facing constitutes the immediate support of the flexible diaphragm 1, the resulting dam construction differing from prevailing practices in which the ultimate diaphragm is laid directly on the rock base, hence is at the 90 mercy of any internal disturbance which will unsettle the position of the rocks.

The merit of the gravel facing 14 is better explained as follows:—Assume that from an earthquake or some other cause, the rocks in the base 2 have settled as indicated at 15 (Fig. 1), producing what would appear as a large depression 16. This depression is communicated to the gravel facing 14 which immediately flows into the depression 16 from all sides and above over a wide area adjacent to the flexible diaphragm 1.

It can easily be seen that instead of a drop of the approximate distance 17 (Fig. 1) being communicated to the flexible diaphragm 1 the maximum amount of drop of the diaphragm would scarcely be noticeable, and if detected at all would appear as a large shallow depression represented by the easy lowering over a very wide area of the diaphragm into the shallow concavity in the gravel facing 14.

It is thus the purpose of the gravel facing 14 to distribute any settlement in the rock base 2 over a large superficial area. The diaphragm 1 will thus show but a slight lowering over a wide area, and will not suffer a sudden drop and consequent breakage immediately above where the basic settlement 125 occurred.

The angle of repose 18 of the gravel facing 14 is substantially parallel to the mean face 130

line 11 (Fig. 2) of the auxiliary fills 4, 5, etc. This angle of repose 18 is obtained by raking because simply dumping would not do. Again, the gravel facing is not applied 5 in its entirety at the beginning, but is built up as the construction of the dam progresses. This is equally true of the flexible diaphragm 1, and the construction of this is as follows:—

An asphaltic solution 19 is sprayed on or 10 otherwise applied to the surface of the gravel facing 14. Its purpose is to prevent the fines of the concrete mix from passing into the gravel fill. The flexible diaphragm 1 comprises a foundation slab 20 and a water tight 15 membrane 21. The slab is laid on the impervious asphaltic skin or covering 19. It comprises succeeding courses of large blocks (Fig. 5) of any suitable dimension, but in this case are regarded as 16 feet square in top 20 surface area.

They will be laid in alternation across the canyon. To give an illustration, the blocks 22, 24, etc. (Fig. 5) would be laid (in the third course for example) and permitted to 25 set, whereupon blocks 23, etc. would be laid in the spaces between. This enables complete shrinkage of the blocks 22, 24, etc. before the intervening blocks are placed.

In laying the fourth course, the same plan 30 would be followed. All of the blocks are laid in horizontal courses across the canyon 13 (Fig. 7) in alternation, the spaces between blocks being filled later to complete a given course. After the foundation slab is completed, the outer surface is coated with a 35 thin wash of asphalt 20 (Fig. 3).

It has been stated that the auxiliary fill 4 is begun after the main rock-fill has been carried to only a part of its ultimate height. 40 This partially explains an advantageous structural principle according to which the finishing of the dam can be proceeded with while the dumping of the rock-fill is yet in progress.

45 The process here involved is to carry the main rock-fill to a certain height, as explained, apply the auxiliary fill 4, next apply the gravel cushion to the requisite depth and finally apply the concrete diaphragm. 50 These various steps of the work can be carried out at virtually the same time so that there need not be great delays between any of the stages of construction.

Reinforcing material 25 (Fig. 5) is incorporated in the courses of blocks. The reinforcing rods run in both directions through the centers of the blocks. Every third block in the succeeding higher course is equipped with a rib 26 (Fig. 5). These ribs are staggered in position. They are sunk into the gravel facing 14 and tend to prevent any sliding of the flexible diaphragm 1 that might occur especially among the lower blocks of the slab 20.

65 Inasmuch as the pressure of water is

greater at the bottom of the dam than at the top the slab 20 is made thickest at the bottom, and the thickness is graduated to a predetermined minimum dimension at the top as suggested in Figure 1. The thickness of 70 succeeding courses of slab blocks is easily regulated during the construction of the dam.

Considerable importance is attached to the connection of the toe or bottom of the dam 75 with bed rock. This is accomplished by digging a trench 27 (Figs. 1, 2 and 4) and filling this with concrete 28. This concrete fill becomes an abutment on which the water proof diaphragm has a footing. In placing this concrete fill the use of a suitable form 80 produces the contour 29 which comprises a succession of rectangular recesses or steps on which the first course of blocks of the slab 20 rests.

This course is different from the rest, hence 85 is designated 30 (Figs. 1, 2 and 4) for distinction. The blocks in this course comprise concrete laminations 31. Each layer is laid separately and in alternation in the exact manner previously described for the third and succeeding courses (Fig. 5). The blocks in the various layers are so laid as to stagger or break the joints 32 (Fig. 4). A thin wash or spray of asphalt 33 is applied to the layers as completed.

Reinforcing rods, originally set in the concrete fill 28 (Fig. 4) are later incorporated in the various layers of the course 33 as these are completed. The result of this construction is a laminated course rigidly connected 90 to the fill 28 but projecting upwardly beyond the spur 35 thereof to the following advantage:—It is expected that some cracks will develop in the laminations of the bottom course 30. This is likely because of the enormous weight concentrated on the footing of the dam. The possibility of cracking is also present by virtue of the laminated course 30 resting in part on the gravel facing 100 105 110 115 120 125 130 135 140 145 150 155 160 165 170 175 180 185 190 195 - blocks of foundation slab 20 therebeneath. The blocks of the membrane 21 are reinforced in both directions (Fig. 5) as at 38. They are so laid that the superimposed joints 5 will be broken. However, the crossing of joints cannot be prevented, and where this occurs copper water stops 39 are so placed as to form a bottom. For illustration, joint 10 40 (Fig. 6) in the water tight membrane 21 would be open to the joint 41 between adjacent blocks in the foundation slab 20 were it not for the water stop 39. This stop is only a relatively small plate that is laid where two joints cross.
- 15 Reverting to the blocks of the water tight membrane 21, these are generally of the same size as the blocks in the foundation slab 20. However, rather than being graduated in thickness from base to crest, as are 20 the blocks in the foundation slab, they are of equal thickness throughout. In order to make the membrane 21 water tight the joints 42 (Fig. 5) in the blocks will be filled with a mixture of asbestos and asphalt in such 25 proportions that when tamped with an appropriate hammer the asphalt will just be flush with the surface.
- Anchors 43 are embedded in the slab 20, later to be bent over at 44 (Fig. 3) so as to 30 be confined within the blocks of the membrane 21. These anchors may take any preferred shape. Their purpose is to keep the blocks of the membrane 21 centered upon the foundation slab 20. However, these blocks 35 are capable of some expansion and contraction in reference to the anchors 43, imparting to the diaphragm 1 that degree of flexibility necessary to its functioning as already outlined.
- 40 In addition to the foregoing construction the invention also resides in the method of making the dam. The outstanding steps of this are as follows:—First the production of the mean face line 11 (Fig. 2) at a lesser angle than the natural angle of repose 8 assumed by the rock in dumping. The arrival 45 at the mean face 11 requires a building up of the face of the rock fill 8 by a succession of auxiliary fills 4, 5, etc.
- 50 The next step resides in the application of the mobile cushion 14 which has the quality of disseminating any internal relaxation of the rock base 2. The gravel will flow into the depression 16 from all sides and so have the 55 effect of extending the depression over a wide area, but in doing so to so lessen the depression that its effect on the diaphragm 1 will hardly be noticed.
- Next to this is the step of building up the 60 flexible diaphragm 1. This comprises the foundation slab 20 and the water tight membrane. The joints between the blocks in this membrane are made water tight by the asbestos asphalt joint compound.
- 65 I claim:—

1. A dam comprising a rock fill base, a water tight diaphragm spaced from the face of the rock fill base, and an interposed mobile stratum of loose, free-moving elements resting on the rock fill base and supporting the diaphragm, being capable of flowing into a depression in the rock fill base and thus maintaining the support of the diaphragm. 70
2. A dam comprising a rock fill base, a watertight diaphragm spaced from said base and consisting of a plurality of blocks with means for connecting them to render the diaphragm flexible, and a stratum of gravel interposed between the rock fill base and diaphragm resting on said base. 75
3. A dam comprising a rock fill base, a flexible watertight covering diaphragm, and a fluent gravel stratum means between the base and diaphragm, yielding to a relaxation of the rock fill base but disseminating the resulting depression over a wide area beneath the diaphragm. 80
4. A dam comprising a rock fill base having a mean face line of a lesser inclination than the natural angle of rock-repose, a covering watertight diaphragm spaced from said base and having its exposed surface substantially parallel to said face line, and a gravel stratum interposed between the diaphragm and rock fill base providing the immediate support of the diaphragm. 85
5. A dam comprising a rock fill base, a gravel facing on the rock fill base, a water proof diaphragm applied to the gravel facing, and ribs projecting from the diaphragm into the gravel facing. 100
6. A dam comprising a rock fill base, an abutment adjacent to the base said abutment including a spur, a gravel facing on the rock fill base confronting and contacting the spur, and a water proof diaphragm covering the gravel facing and having its footing on the abutment. 105
7. A dam comprising a rock fill base, an abutment adjacent to the rock fill base, said abutment having a stepped contour and a spur, a gravel facing applied to the rock fill base and contacting the spur, a water proof diaphragm laid on the gravel facing, and a bottom course included in said diaphragm being composed of laminations having footings on the stepped contour of the abutment. 115
8. In a dam, a base having a face with a plurality of set backs from bottom to crest, a mobile gravel facing applied to the face and resting in part on the set backs to prevent any tendency toward rolling down and piling up at the bottom, and a water proof diaphragm covering the gravel facing. 120
9. In a dam, a base having an inclined face, a gravel facing applied to said face, an adjacent abutment having a spur with which a part of the facing contacts, reinforcing rods embedded in the abutment and extending over both the spur and a part of a facing, 125

a water proof diaphragm laid on the facing, and a bottom course included in the diaphragm, consisting of laminations formed around said extending reinforcing rods and having chief support upon said spur.

10. The herein described method consisting of making a base by dumping rocks to form a succession of set backs and produce a mean face line of a lesser inclination than the angle of repose of the rocks, dumping a gravel cushion on said set backs and raking the face of the cushion until substantially parallel with said mean face line, coating the cushion with an impervious skin, and building a 15 water proof diaphragm in stages over said skin.

11. The herein described method consisting of dumping a main rock-fill to only a portion of its ultimate height, dumping an auxiliary fill at the base of the main rock-fill 20 preparatory to disposing the face of the dam at an inclination less than the angle of repose of the main rock-fill, applying a gravel facing to the auxiliary fill, constructing a water-proof diaphragm on the gravel facing, 25 and continuing the foregoing operations in progressive order toward the top of the dam until the latter is completed.

12. A dam comprising a rock fill base, a 30 layer of gravel covering the upstream face of the base, and a water-proof diaphragm supported by said gravel layer.

JAMES B. GIRAND.
